Des. 96,500

UNITED STATES PATENT OFFICE

96,500

DESIGN FOR A CYCLE SADDLE SEAT

Harry M. Pryale, Pontiac, Mich.

Application May 13, 1935, Serial No. 56,808

Term of patent 7 years

To all whom it may concern:

Be it known that I, Harry M. Pryale, a citizen of the United States of America, residing at Pontiac, in the county of Oakland and State of Michigan, have invented a certain new, original, and ornamental Design for a Cycle Saddle Seat, of which the following is a specification, reference being had therein to the accompanying drawing, forming a part thereof, in which the figure is a perspective view of a saddle seat showing my new design.

I claim:

The ornamental design for a cycle saddle seat substantially as shown.

HARRY M. PRYALE.

DISCLAIMER

Des. 96,500.—Harry M. Pryale, Pontiac, Mich. A CYCLE SADDLE SEAT. Patent dated August 6, 1935. Disclaimer filed February 19, 1936, by the patentee.

Hereby enters this disclaimer to said ornamental design for cycle saddle seat as illustrated and described in said Letters Patent.
